CLAIM

The ornamental design for a display screen or portion thereof with graphical user interface for a game, as shown and described.

DESCRIPTION

FIG. 1 is a front view of a display screen or portion thereof with graphical user interface for a game showing my new design; and,

FIG. 2 is an enlarged portion of FIG. 1 showing the claimed subject matter isolated and enlarged, for clarity of illustration.

The outermost dashed broken line depicts a display screen that forms no part of the claimed design. The remaining, thinner broken lines illustrate portions of the graphic user interface that form no part of the claimed design. The remaining, thicker broken lines identify the enlarged portion of FIG. 1 shown in FIG. 2 and form no part of the claimed design.
